UNITED STATES PATENT OFFICE.

STEPHEN LANE, JR., OF ENGLEWOOD, NEW JERSEY.

DESIGN FOR ALE-PUMPS.

Specification forming part of Design No. 6,700, dated June 10, 1873; application filed May 16, 1873.

CASE B.

To all whom it may concern:

Be it known that I, STEPHEN LANE, Jr., of Englewood, county of Bergen and State of New Jersey, have invented a Design for Ale-Pumps, of which the following is a specification:

The nature of my design is fully set forth in the following description and annexed drawing; and consists in the novel and peculiar shape and arrangement of that portion of the pump included between the two horizontal planes $x x y y$.

The boxes A A, instead of being round, as is universally the case with pumps at present in use, are made square, and instead of the handles $a a$ of the pumps passing through and working in slots in the boxes A A they are pivoted to suitable bearings C C, secured on the top of

the boxes. B is the recess, composed of marble, &c., situated between the boxes A A, and just above this the cocks for the different liquids are arranged in a row.

My design consists in the arrangement and configuration of the boxes A A and handles $a a$, and having an upper box, $b b$, to which the cocks are affixed, placed over the boxes A A, and in the arrangement and configuration of that portion of the pump included between the two horizontal planes $x x y y$; and

What I claim is—

The design for an ale-pump, substantially as described, and shown in the accompanying drawing.

Witnesses: STEPHEN LANE, JR.
